UNITED STATES PATENT OFFICE.

TERENCE F. CURLEY, OF BROOKLYN, NEW YORK.

DESIGN FOR A KNIFE-SHARPENER.

56,227.

Specification for Design. Patented Aug. 31, 1920.

Application filed April 2, 1920. Serial No. 370,884. Term of patent 7 years.

To all whom it may concern:

Be it known that I, TERENCE F. CURLEY, a citizen of the United States, and a resident of the city of New York, borough of Brooklyn, in the county of Kings and State of New York, have invented a new, original, and ornamental Design for a Knife-Sharpener, of which the following is a specification, reference being had to the accompanying drawings, forming a part thereof.

Figure 1 is a front elevation of a knife sharpener showing my new design;

Fig. 2 is a rear elevation of the same; and

Fig. 3 is an edge view of the same.

I claim:

The ornamental design for a knife sharpener as shown.

TERENCE F. CURLEY.
